DEZSÖ SZIGETI, OF NEW YORK, N. Y.

SUPPORT FOR VIOLINS, VIOLIN BOWS, AND THE LIKE

Application filed June 20, 1927. Serial No. 199,903.

My present invention relates to means for supporting a violin, and also, if so desired, a violin bow, especially means of the general character specified which are adapted for convenient use with the usual music stand or desk, and aims to devise means of the general character specified which are simple in construction, which may be readily and conveniently fabricated, and which, in use, are very well adapted for the convenient and secure positioning of a violin and violin bow, when the same are not in use but are desired to be securely positioned for immediate availability when the instrument must be used again. Other objects and advantages of the devices of the present invention will in part be pointed out in detail hereinafter and will in part be obvious to those skilled in the art to which the present invention relates.

In the accompanying specification I shall describe and in the annexed drawing show an illustrative embodiment of the present invention. It is, however, to be clearly understood that my invention is not limited to the specific embodiment thereof herein shown and described for purposes of illustration only.

Referring to the drawing, wherein I have illustrated the aforesaid illustrative embodiment of the present invention:

Fig. I is a view in side elevation showing the aforesaid illustrative embodiment of the present invention;

Fig. II is a top plan view of the same; and Fig. III is a front view of the same.

Referring now to the aforesaid illustrative embodiment of the present invention, and more particularly to the drawing illustrating the same, 10 indicates the main body portion or connecting and supporting member forming a part of said embodiment. The member 10 preferably consists of a strip of metal of sufficient strength to serve as suitable supporting and connecting means for the remaining portions of the device. The member 10 preferably has the shape and configuration shown in the drawing, although other forms of connecting member may be conveniently employed.

Adjacent one end of the same, the member 10 carries a clamping portion 11, preferably

in the form of a spring clamping device having the spring arms 12 and 13 adapted to clasp between them the neck of the violin or the like.

Adjacent its other end, the member 10 is provided with means, generally designated by reference character 14, for attaching the device as a whole to a music desk or stand or other suitable supporting means. For this purpose the member 10 may be provided opposite the end to which the clamping member 10 is attached, with a plurality of bracket members 15 and 16, suitably attached with the necessary rigidity to the member 10. One of these members, as the lower member 16, is preferably provided with means, generally designated by reference character 17 and, for example, in the form of an adjustable clamping screw or similar device, for attaching the device with the necessary rigidity to the music desk, stand or other suitable support for the device.

Extending in the opposite direction from the clamping means 14 is means, generally designated by reference character 18, for supporting the violin and also, if desired, the violin bow, and adapted to receive the weight of the instrument and to lock the same securely in position in such a manner that the same may be readily released for instant use. For this purpose, I prefer that the means 18 shall comprise a plurality of supporting members 19 and 20. I prefer that one of the supporting members, as the member 19, shall be relatively short and shall have the key-engaging portion 21. I prefer that the other supporting member 20 shall be relatively long and shall have the key-engaging portion 22 and the bow-receiving and supporting portion 23. I prefer also that the members 19 and 20 shall be hingedly attached to a suitable portion of the main connecting or supporting member 10 and shall be provided with the springs 19' and 20', respectively, so as to normally spring 90 press the supporting members 19 and 20 together, so as to cause the same to bear with the necessary pressure against the scroll or head of the violin adjacent the corresponding key portions of the same, these being the 100

keys that control the E and G strings of the violin, respectively.

This completes the description of the aforesaid illustrative embodiment of the present invention. The structure of said embodiment will, it is believed, be clear from the foregoing description. Likewise the manner of assembling the same will be clear from the foregoing description. In use, the musician loosens the clamping screw or other member by unscrewing the same a sufficient amount in order to permit the entrance of a portion of the music desk or stand between the bracket portions 15 and 16. Thereupon the member 17 is operated in the opposite direction in order to securely clamp the device on the desired portion of the music desk or stand.

When the musician desires to have the violin and bow supported by the device, he spreads the supporting members 19 and 20 apart against the action of the springs 19' and 20', respectively, and slips in the head or scroll of the violin so that the key controlling the E string rests on the portion 21 of the member 19, while the key controlling the G string rests on the portion 22 of the member 20. At the same time, the neck of the violin is slipped in between the spring clamping portions 11 and 12, thus securely positioning the violin. The bow may now be supported on the portion 23. The violin has been generally indicated by reference character V and the bow by reference character B.

When it is desired to remove the violin and the bow, the supporting members 19 and 20 may be spread apart against the action of the springs 19' and 20', respectively, and the bow and violin quickly removed. It will thus be noted that the device provides convenient means for securely positioning the violin and bow until the same are desired to be used again, and permits their ready removal for use. This completes the description of the manner of using the aforesaid illustrative embodiment of the present invention.

Other advantages and superiorities of the devices of the present invention will readily occur to those skilled in the art to which the present invention relates.

50 What I claim as my invention is:

1. Supporting means for a violin and the like, comprising a connecting member, means to attach said connecting member to a suitable support, means associated with said connecting member for engaging the keys of a violin, and means cooperating with said key engaging means for receiving the neck of said violin.

60 2. Supporting means for a violin and the like, comprising a connecting member, spring clamping means adjacent one end thereof for receiving the neck of the violin or the like, means associated with said connecting member for attaching the same to a suitable support and means adjacent the other end of said

connecting member for engaging a plurality of spaced key portions of said violin or the like.

3. Supporting means for a violin and the like, comprising a connecting member, means adjacent one end thereof for receiving the neck of the violin or the like, means associated with said connecting member for attaching the same to a suitable support and means comprising a plurality of hinged spaced members positioned adjacent the other end of said connecting member for engaging a plurality of spaced key portions of said violin or the like.

In testimony whereof I have signed my name to this specification this 13th day of June, 1927.

DEZSÖ SZIGETI.
